PUMP

Francis E. Brady, Jr., Muncie, Ind.

Application September 8, 1941, Serial No. 410,031

4 Claims. (Cl. 103—126)

This invention relates to fluid pumps.

One object of the invention is the provision of a pump construction embodying a pump housing detachably connected to and supported by a frame or bracket which, in turn is adapted for connection to the motor which operates the pump, the frame having passages through which fluid is supplied to or from the pump housing, the construction being such that the pump housing together with the fluid impelling means and a driving member which is mounted in the pump housing may be readily separated as a complete unit without disturbing pipe connections to the frame.

Another object of the invention is the provision of a pump construction embodying the detachable pump unit carried by a separate frame member which in turn is mounted on the motor that drives the pump, the pump unit in which the fluid impelling means is operably mounted with a suitable operating clearance or fit being readily removable from the frame without disturbing pipe connections and without in any way changing the running fits or bearings of the operating parts of the pump.

Another object of the invention is the provision of a construction of the character mentioned in which the frame, to which the pump housing is detachably connected, is detachably supported on one end of the motor housing, and the driving connection between the motor shaft and the fluid impelling means of the pump is established when the pump is applied in its proper position on the pump carrying frame.

Other objects and advantages of the invention will be apparent from the following description, the appended claims, and the accompanying drawings, in which,

Fig. 1 is a side elevation, shown partly in central vertical section through a pump construction embodying the present invention;

Fig. 2 is an end view of the pump assemblage;

Fig. 3 is a central horizontal section showing the pump support and a portion of the motor on which the pump support is carried;

Fig. 4 is a horizontal section through the pump unit taken on the line 4—4 of Fig. 2;

Fig. 5 is a vertical section on the line 5—5 of Fig. 2;

Fig. 6 is an end elevation of the pump supporting frame;

Fig. 7 is an end view of a pump support of a modified construction; and

Fig. 8 is a central vertical section on line 8—8 of Fig. 7 and also showing the pump in supported position.

Referring more particularly to the drawings, in which the same reference numerals have been applied to the same parts in the several views, Figs. 1 to 6, inclusive, show a preferred embodiment of the invention as applied to a pump construction in which the impelling action is obtained by intermeshing gears of a pump unit which is carried adjacent an end of the power means or motor by means of which the pump is driven,

herein shown as an electric motor 10 which may be of any suitable character. Detachably connected to the housing 11 of the motor by means of suitable securing bolts 13 or the like is a bracket or frame 14. One end of this frame fits against the end of the motor housing adjacent the projecting end portion of the motor shaft 12. As shown, the frame 14 has an upwardly arched wall and is provided with an opening 15 through which the end of the motor shaft is accessible.

20 In the frame 14 there are two passages 16 and 17 forming fluid supply and discharge conduits for the fluid supplied to and from the pump. One end of the passage 16 is adapted to be connected to a fluid supply pipe, which may be readily screwed into the threads 18 at a location that is readily accessible, preferably at the top of the frame, and the passage 17 is similarly arranged and adapted to be readily connected to a fluid discharge pipe. The passages 16 and 17 terminate in ports 19 and 20 which are provided in the wall portion 21 of the frame and which, as shown, face in a direction away from the motor. The wall portion 21 of the frame is adapted to be readily secured to the housing 22 of a fluid pump unit, and forms a support for the pump, the ports 19 and 20 being adapted for registration with the inlet and discharge openings of the pump housing. The pump housing together with the pumping means and a drive member or shaft portion

30 connected to the pumping means forms a readily removable unit which may be readily secured to the pump supporting frame as by means of bolts 24, and when the pumping unit is brought into place, its shaft portion is coupled to the end of

35 the motor shaft.

The pumping means includes a fluid impeller or impellers operating with a small clearance and accurately carried in proper position in the housing, the pumping means being shown in

40 Figs. 1 to 6 inclusive as embodying a pair of intermeshing gears 25 and 26 rotatable in the pump chamber 27. The pump chamber is formed by an end wall 28 and a connected pump housing portion 29, these two parts being secured together as by means of screws or bolts 30 which

45

50

55

are removable after the pump housing has been disconnected from its supporting frame. The parts 28 and 29 of the pump housing rotatably support the shaft 31 of gear 26 and the shaft 32 on which the gear 25 is fixed as by means of the key 33. The bearings for these shafts serve to accurately locate the gears in proper intermeshing relation and with the proper minimum clearance between the gear teeth and the arcuate surfaces of the fluid chamber. As the gears revolve, it will be understood that fluid is pumped to the outlet opening 34 of the pump housing from the inlet opening 35, and since these openings register respectively with the ports 20 and 19 of the pump supporting frame, a flow of fluid will take place from the inlet pipe connected to the threads of the passage 16 in the frame and be supplied through a pipe connected to the passage 17. A suitable sealing gasket 36 is provided between the end wall 28 of the pump housing and the carrying wall 21 of the supporting frame to seal the connection between the passages in the frame and the inlet and discharge openings of the pump housing.

As the pump housing is moved into position, by axially moving it towards the motor, a connection is established between the end of the motor shaft 12 and the coupling member 39 which is fixed on the end of the pump shaft 32 and having a keyway which fits over a key 40 on the motor shaft. In the construction shown, the supporting bracket 14 forms a partial enclosure around the end of the motor shaft and around the coupling 39 and protects those parts.

As will now be apparent, the close running fits and accurately made bearings of the operating parts of the pump unit will be maintained when the pump housing is separated from its support 14, and the removal of the pump may be effected without disturbing the connection of the pipe lines leading to the pump. The removable pump housing together with the pumping means and the shaft portion 32, by means of which the latter are driven may be readily removed and replaced by a new pump head by a layman or mechanic without requiring any special tools. The pump head may be rebuilt or repaired by one thoroughly skilled in such work.

Figs. 8 and 9 show a modification of the invention in which the pumping means is a turbine wheel 42 operating in a housing 43. The housing preferably comprises an inner wall 44 and an outer wall portion 45 to which it is connected by screws or bolts 46. These walls provide a fluid raceway 46 in which the turbine blades travel. The impeller 42 is fixed on a shaft 47 which is journalled in the end walls of the housing and has a projecting portion which is adapted to be readily coupled to the end of a motor shaft, a portion of which is shown at 48. The pump housing is detachably mounted by means of securing bolts 49 on a motor supporting frame 50 which is detachably connected by means of bolts 51 to the end of the electric motor 52 by means of which the pump is driven. The bolts 51 are readily accessible through openings 52 in the top and sides of the frame. The openings may be normally covered by a removable cover plate 53 held in place by screws 54. The pump supporting frame 50 is formed to provide passages 55 and 56 forming fluid conducting portions that lead to supply and discharge pipes that may be connected to the pipe connections 55 and 56. The other ends of the passages 55

and 56 terminate in laterally facing ports 57 and 58 which register with the inlet and discharge ports 59 provided in the end wall 44 of the pump. When the pump is positioned on the carrying frame and in driving connection with the motor shaft, the raceway of the pump will be connected to the fluid supply and discharge conduits in the pump supporting frame, and as will be apparent, the pump unit including the shaft 47, the impeller and the housing walls 43 and 44 may be readily separated as a complete unit without disturbing the operating clearances of those parts, and without disturbing the pipe connections leading to the pump supporting frame 50.

While the forms of apparatus herein described constitute preferred embodiments of the invention, it is to be understood that the invention is not limited to these precise forms of apparatus, and that changes may be made therein without departing from the scope of the invention which is defined in the appended claims.

What is claimed is:

1. In combination with a motor having a frame 25 at one end thereof to which fluid supply and discharge pipes are secured, said frame having fluid passages formed therein communicating respectively with said pipes, a detachable self-contained pump unit adapted to be driven by said 30 motor comprising a rotary pump including intermeshing gears, a pump housing member having a recess therein forming a pump chamber for receiving said gears, said housing member also having a recess for locating and accurately 35 defining the position of a side of said pump chamber, a housing wall adapted to be received in said recess to form said side of said chamber and complete the closure thereof, means for securing said housing wall directly to said housing 40 member with said gears therebetween in predetermined operating relation thereto, means engageable with said frame for assembling said unit in operative position and drawing said unit tightly against the frame with said housing wall 45 located in abutting contact with the frame, said wall having cooperating fluid passages arranged to register and establish communication with said fluid passages in said frame, and a detachable drive connection from said rotary pump to said motor adapted to be established upon assembly of said unit on said frame.

2. In combination with a motor having a frame at one end thereof to which fluid supply and discharge pipes are secured and having fluid 55 passages formed therein, a detachable self-contained pump unit adapted to be driven by said motor comprising a rotary pump including intermeshing gears, inner and outer pump housing walls on opposite sides of said gears, said outer wall having a recess forming a pump chamber and a recess of greater radial extent than said pump chamber for receiving and accurately locating said inner housing wall therein, means extending through said inner wall and engageable with said outer wall for securing said housing walls directly to each other with said gears therebetween in predetermined operating relation in said pump chamber, means extending through the outer of said walls and engageable with said frame for assembling said unit in operative position and drawing said unit tightly against the frame with said inner wall located in abutting contact with the frame, said inner wall having cooperating fluid passages arranged to register and establish communication with

said fluid passages in said frame, and a detachable drive connection from said rotary pump to said motor adapted to be established upon assembly of said unit on said frame.

3. In combination with a motor having a frame at one end thereof to which fluid supply and discharge pipes are secured and having fluid passages formed therein, a detachable self-contained pump unit adapted to be driven by said motor comprising a pair of intermeshing gears, inner and outer pump housing walls on opposite sides of said gears in predetermined close fitting relation thereto, means for securing said housing walls directly to each other with said gears therebetween in predetermined operating relation thereto, means carried entirely by said walls and free of direct contact with said frame for rotatably supporting said gears, means extending through the outer of said walls and engageable with said frame for assembling said unit in operative position and drawing said unit tightly against the frame with said inner wall located in abutting contact with the frame and said securing means concealed by said frame and inaccessible in said assembled relation, said inner wall having cooperating fluid passages arranged to register and establish communication with said fluid passages in said frame, and a detachable drive connection from said pump unit to said motor adapted to be established upon assembly of said unit on said frame.

4. In combination with a motor having a drive shaft and a frame at one end thereof to which fluid supply and discharge pipes are secured and having fluid passages formed therein, a detachable self-contained pump unit adapted to be driven by said motor comprising a pair of intermeshing gears, a shaft for each of said gears, pump housing walls on opposite sides of said gears forming a pump chamber and journaling each of said shafts therein, one of said shafts projecting beyond one of said pump walls and out of direct supporting contact with said frame forming a detachable driving member adapted to be connected with said motor shaft, means extending through one of said pump walls for securing said walls directly together with said gears therebetween, said walls having cooperating interfitting parts providing for maintaining said two walls in predetermined relation to each other and with said gears in predetermined close fitting operating relation therebetween, and means extending through the outer of said walls and engaged within said frame for drawing said unit tightly against the frame with the other said wall in abutting contact therewith providing for separation and removal of said unit as an assembled operative pump, said other wall having fluid passages formed therein adapted to register with said fluid passages of said frame in the assembled position thereof.
